UNITED STATES PATENT OFFICE.

HOWARD H. HAMAN AND WILLIAM E. SCHMIDT, OF THREE OAKS, MICHIGAN,
ASSIGNORS TO THE WARREN FEATHERBONE CO., OF THREE OAKS, MICHIGAN,
A CORPORATION OF MICHIGAN.

BELTING.

1,325,788.

Specification of Letters Patent. Patented Dec. 23, 1919.

Application filed February 5, 1919. Serial No. 275,110.

To all whom it may concern:

Be it known that we, HOWARD H. HAMAN and WILLIAM E. SCHMIDT, both citizens of the United States, and both residing at

5 Three Oaks, in the county of Berrien and State of Michigan, have invented certain new and useful Improvements in Belting, of which the following is a specification.

Our invention relates to improved means 10 for securing stiffening strips to fabric, more particularly for securing transverse stiffening strips to fabric belting.

For stiffening fabric it is customary to sew strips of other fabric or tape along the 15 longitudinal edges to the fabric to form pockets into which stiffening strips such as whalebone or featherbone are inserted. During bending or wear of the fabric the strips, when thus merely slipped into the pockets, 20 may become displaced, turned or twisted, particularly when they are subjected to endwise pressure. The object of our invention is to prevent such displacement, turning or twisting and to keep the stiffening or stay 25 members always in flat condition with reference to the base fabric. This is of particular importance in belting where the short transverse stiffening members are subjected to longitudinal pressure and abrupt bending.

30 In accordance with our invention the stiffening material or stays are sewn or otherwise secured to strips of fabric or tape and these strips of fabric or tape applied to the fabric to be stiffened with the stiffening material 35 between the tape and fabric and the tape then sewn to the fabric along its edges. The stays are thus not only held by the walls of the formed pockets but are also rigidly secured to one wall thereof and twisting, turning or displacement is prevented.

On the accompanying drawing our improved construction and arrangement is clearly shown:

Figure 1 is a plan view of a length of 45 belting showing transverse stiffening strips applied thereto at intervals.

Fig. 2 shows a length of tape to which a stay has been sewn.

Fig. 3 is a sectional view on plane 3-3, 50 Fig. 2.

Fig. 4 is an enlarged sectional view on plane 4-4, Fig. 1.

Fig. 5 is an enlarged sectional view on plane 5-5, Fig. 1, and

Fig. 6 is an end view of the tape with a 55 stay secured thereto and showing the longitudinal sides of the tape folded under before sewing to the base fabric.

10 represents a length of base fabric or belting whose longitudinal edges are protected by binding 11 and 12. 13 represents the transverse pieces of tape sewn to the base fabric and providing pockets for the stiffening stays or strips. In Fig. 2, 14 represents a length of tape to which a stiffening strip or stay 15 is secured longitudinally as by stitching 16, the strip being narrower than the tape to permit the sides 17 and 18 of the tape to be turned under, as shown in Fig. 6. The tape with the stiffening strips or stays secured thereto are then laid on the base fabric to be stiffened with the stays between the tape and the fabric. The tape lengths along their turned-in sides are then sewn to the fabric by stitching 19 and 20 which can very quickly be done by a two-needle sewing machine. The stiffening strips are now held in pockets formed by the base fabric and tape lengths and are further secured to one wall of the pockets 80 and are prevented from twisting, turning or becoming displaced, and will always lie flat.

To form belting the tape lengths can be sewn along parallel lines to the base fabric and then the fabric cut into proper belting 85 widths in a direction at right angles to the stays, and then binding applied to the belting thus formed, the binding passing over the ends of the transverse stays and their enclosing pockets. Or, after the stiffening material has been sewn to tape lengths, the 90 lengths can be cut up into pieces of a length equal to the width of the previously cut belting lengths to which they are to be applied. The small tape lengths are then sewn onto 95 the belting and the binding 11 and 12 applied, as shown in Fig. 1.

Not only are the strips prevented from turning or twisting but the mode of application is greatly simplified. By the old 100 way the tape was first sewn on to the base fabric to form the pockets and the stays inserted therein. If the tape was not guided straight through the machine during sewing or if the stitching lines came too close together it was difficult to insert the stays. With our improved procedure the stays are applied to the base fabric simultaneously 105

with the pocket forming tape which supports them and the stays act to guide the tape during stitching of the same to the base fabric. The stays could, of course, be 5 secured to the base fabric by stitching through the tape, base fabric and stays after the tape has been applied and the stays inserted therein. However this will leave transverse stitching lines on the outside of 10 the belting which would be more or less unsightly. With our arrangement such transverse stitching lines appear only on the back of the belting or stiffened fabric.

We do not, of course, desire to be limited 15 to the exact construction, arrangement and operation shown and described, as modifications are no doubt possible which would still come within the scope of the invention. We claim as follows:

20 1. The combination with base fabric, of strips or tape lengths secured thereto along their edges to form pockets, and stays in said pockets, said stays being stitched to one side of said pockets.

25 2. The combination of base fabric to be stiffened, of tape lengths or strips sewn along their edges to the fabric to form pockets, and stays or stiffening members in said pockets, said stays or stiffening members being sewn to said tape or strip lengths forming said pockets.

30 3. The combination with fabric to be stiffened, of tape lengths or strips, stays or stiffening members secured to said tape lengths or strips intermediate their side

edges, said tape lengths being applied to the fabric with the stiffening members against the fabric, the tape lengths being sewn to the fabric along their longitudinal edges. 40

4. In belting, the combination of the base fabric, transverse strips or tape lengths sewn to the fabric along their edges to form pockets therewith, stiffening members or stays within said pockets, said stiffening members or stays being sewn to the transverse strips or tape, and binding along the edges of said fabric. 45

5. In belting, the combination of the base fabric, transverse strips or tape lengths sewn to the fabric along their edges to form pockets therewith, stiffening members or stays within said pockets, said stiffening members or stays being sewn to the transverse strips or tape, and binding along the edges of said fabric. said binding receiving the ends of said tape lengths and the stiffening members secured thereto. 50

6. The process of stiffening fabric which consists in securing stiffening members or stays to tape lengths, then applying the tape lengths to the fabric with the stiffening stays against the fabric, and then sewing the tape lengths along their edges to the fabric. 60

In witness whereof, we have hereunto subscribed our names this 30 day of January, A. D., 1919.

HOWARD H. HAMAN.
WILLIAM E. SCHMIDT.
